(57) **CLAIM**

The ornamental design for a display screen or portion thereof with graphical user interface, as shown and described.

DESCRIPTION

The FIGURE is a front view of a display screen or portion thereof with a graphical user interface showing our new design.

The outermost broken lines in the FIGURE show an electronic device having the display screen or portion thereof. The electronic device and the display screen or portion thereof form no part of the claimed design. The other broken lines in the FIGURE show portions of the graphical user interfaces that form no part of the claimed design.

FUNSCOPE

Can you find all the characters hidden
throughout the house? It's Funscope!

Search for the secret symbol in each
room. When you find one, click on the
camera icon.

Then, point your phone or tablet's
camera at the symbol to find that room's
character.

Good luck!
